UNITED STATES PATENT OFFICE.

WILLIAM DUBILIER, OF NEW YORK, N. Y., ASSIGNOR TO DUBILIER CONDENSER AND RADIO CORPORATION, A CORPORATION OF DELAWARE.

ELECTRICAL CONDENSER.

Application filed February 14, 1924. Serial No. 692,869.

To all whom it may concern:

Be it known that I, WILLIAM DUBILIER, a citizen of the United States, residing at New York city, in the county of New York and State of New York, have invented certain new and useful Improvements in Electrical Condensers, of which the following is a specification.

My invention relates to improvements in condensers, especially electrical condensers for radio apparatus and other electrical devices.

An object of the invention is to provide a condenser that is simple and compact in form, capable of maintaining a constant pre-determined capacity, and durable in construction.

Another object of the invention is to provide a condenser having means which are a part of the structure of the condenser, for exerting a continuous uniform pressure upon the stack or body, consisting of alternate sheets or leaves of insulating material and conducting material, so that not only does the capacity of the condenser remain perfectly constant throughout the period of the life of the condenser, but also the formation of cracks and other spaces between the conducting sheets and the dielectric sheets between same, is entirely prevented, and reduction of efficiency in practice is thus avoided.

A further object of the invention is to provide a condenser having one or more members for engaging and gripping the parts of the condenser to hold the same firmly together, such member or members being designed to be worked so as to secure with equal firmness the parts of condensers of different thicknesses, and thus being capable of utilization in the manufacture of condensers of different capacities.

Still another object of the invention is to provide a condenser, the body of which comprises a plate herein termed the base or mounting plate and another plate known as the cover plate, said mounting plate and said cover plate holding the stack consisting of alternate sheets of dielectric and conducting material tightly between them, said plates being preferably made of some strong rigid insulating material, and one of said plates having one or more extensions, to each of which can be fastened a clip, which over-laps the edge of the other plate, acting to

hold the two plates together with the sheets or leaves of dielectric and conducting material compressed tightly between the opposed faces of the plates.

A still further object of the invention is to provide a condenser which includes a pair of plates with alternate sheets of dielectric and conducting material between them and with one or more clips or fastening devices to hold the plates together, each of said clips or fastening devices having tips which can be used as lugs for enabling the condenser to be soldered or otherwise affixed to a conductor or support when it is to be connected in circuit.

These and additional objects and advantages of my invention will appear from the following description taken with the accompanying drawings which illustrate several embodiments of the principle of my invention. The disclosure, however, is explanatory only and I may make changes not necessarily shown, but embraced within the scope and spirit of the invention as indicated by the broad and general meanings of the terms in which the appended claims are expressed.

On the drawings, Figure 1 is a top view of a condenser according to my invention.

Figure 2, a bottom view thereof.

Figure 3, an end view thereof.

85

Figure 4, a side view of same.

Figure 5 is a plan view of the base or mounting plate of a condenser according to my invention.

Figure 6 is a plan of the top or cover plate therefor.

Figures 7, 8 and 9 show respectively a plan view of a sheet of conducting material, a sheet of insulating material or dielectric, and a second sheet of conducting material to be of opposite polarity with respect to the first sheet, arranged in the positions which they will occupy with respect to one another, and the base plate, when the condenser is made up.

Figure 10 is a longitudinal sectional view through one of the clips which are fastened to the base plate to engage the cover plate.

Figure 11 is a perspective view of a clamping member for gripping the outside of the condenser.

Figure 12 is a diagrammatic view, showing how this clamp can be employed for condensers having bodies of different thicknesses.

110

Figure 13 is a perspective view of a resilient element which is included in the structure of the condenser to exert pressure upon the sheets of dielectric and conducting material.

Figure 14 is a perspective view of a condenser containing this resilient element, to show the function thereof.

Figure 15 is a perspective view showing another form of such an element.

Figure 16 is a view similar to Figure 14, showing the manner in which the resilient element of Figure 15 is made to serve its purpose.

Figure 17 is a perspective view of a holding clip having an integral portion adapted to engage and support one end of a grid leak.

Figure 18 is a side view of a condenser showing the manner of use of the clip shown in Figure 17.

Figure 19 is a perspective view, showing a modified condenser according to my invention, with only one end of the base plate extended.

Figure 20 is a diagrammatic view, showing how the electrical connections can be made to the conducting sheets of the condenser of Figure 19.

Figures 21, 22 and 23 each show a conducting sheet for the condenser of Figure 19, to illustrate how this condenser can comprise three sets or groups of conducting sheets each to be joined to a different terminal, so that this condenser will afford different capacities by the use of any two of the three groups or sets.

Figures 24, 25, 26 and 27 show respectively a top view, an end view, a side view and a bottom view of another type of condenser according to my invention, comprising a base or mounting plate having only one end extended.

Figure 28 shows a grid leak block to be mounted upon one end of a condenser according to my invention, to support one end of a grid leak.

Figures 29 and 30 are side views of the last named type of condenser showing how this grid leak block can be employed to carry a grid leak in series or in parallel with a condenser.

Figures 31 and 32 are top and side views of another type of condenser according to my invention, and

Figures 33 and 34 are side views of further modifications.

On the drawings, the same numerals identify the same parts throughout.

Referring first to Figures 1, 2, 3, 4, 13 and 14, in the particular description of what the drawings present, I employ the numeral 1 to indicate the so called stack or body of the condenser, made up of condenser elements consisting of sheets of conducting mate-

rial, such as tin foil, and sheets of insulating or dielectric material, such as mica, to separate the sheets of tin foil from one another. This stack of condenser elements is clamped tightly between a pair

of face plates, consisting of a base or mounting plate 2, and a top or cover plate 3. The

stack 1, and plates 2 and 3, constitute the

body of the condenser; and this body comprises resilient means, preferably in the

form of a bent or curved spring plate 4, having its convex face arranged so as to be

caused to exert pressure uniformly over the

entire area of the stack, to press the dielectric and conducting elements firmly together.

Around the body of the condenser and engaging both of the face plates, I place a band clamp 5, which extends across the

top or cover plate 3, and has its ends bent over to grip the outside face of the base plate

2. The purpose of this clamping member

5, is to keep the plates 2 and 3 from bending, also to hold these two plates firmly

against the stack and help to flatten out the

spring plate 4. As shown in the drawings, the clamp 5 is in central transverse position.

I provide the base plate 2, with extensions 6 at its opposite extremity and fastened to

each of these extensions is a clip 7, secured

by suitable means such as eyelet rivets 8, and

having such a shape, that these clips overlap

the adjacent ends of the plate 3, gripping

these ends as tightly as required to draw the

cover plate 3 down and press out the spring

plate 4 flat between the cover plate, and the

top of the stack, so as to make this spring

plate 4 exert the amount of pressure desired

upon the stack 1 and prevent the formation

of cracks, or other spaces between the dielectric and conductive elements of which the

stack is composed. These clips, also the

clamp 5, thus serve as securing or clamping

means to hold the plates 2 and 3, and the

stack 1, between them firmly together, and

to keep the plate 4 pressed out flat under

the plate 3; and the clamp 5 as already

stated, serves to strengthen the middle of

the condenser, keeping the body of the con-

denser straight, and preventing it from

breaking or bending, when in use.

The plate 1, and clips 6 also serve as a

clamp, engaging the ends of the cover plate

3, to secure this plate, the stack 1 and spring

plate 4, tightly together, with the pressure

required; and thus act in the same way, and

in cooperation with the clamp 5.

The face plates, 2 and 3, are preferably

made of bakelite, or some other stiff and

rigid insulating material, although I do not

always wish to be necessarily limited to in-

sulation for this purpose. In some instances

too, the top or cover plate 3 can be omitted

and the overlapping extremities of the clips

7 can be made to grip the opposite edges

of the plate 4 direct, to press this plate out

flat against the top of the stack 1, the band clamp 5 being placed around the top of the condenser tightly in transverse central position as before; such a construction being shown in Figure 33. Further, I do not necessarily wish to be limited to placing the spring plate 4 on the top of the stack 1, as I may locate it in other positions and secure the same result. In some cases too, I 10 may dispense with this spring plate, and employ only the base plate with extensions, the stack thereon, and the band clamp 5, as indicated in Figure 34.

The shape of the base plate 2 and cover plate 3 is shown in Figures 5 and 6. The numerals 9 in the two extensions 6 of the base plate 2, indicate apertures for the eyelet rivets 8, similar apertures being provided in the clips 7. In the opposite edges of the base plate 2, and adjacent the middle thereof are recesses 10, the plate 3 having similar recesses 11, and the spring plate 4 having similar recesses 12. When the condenser is assembled, the recesses 10, 11 and 12 in each of the adjacent edges of the plates 2, 3 and 4 will register or coincide, and the end portions of the clamp 5, which extend across the edges of the plates 2, 3 and 4 to grip the lower face of the plate 2, will be received within the recesses 10, 11 and 12 to keep the clamp in central position, holding it against sidewise movement. The plate 4 will also be held against sidewise movement and this plate may or may not 35 make contact with the clamp. As shown in Figure 11, the main portion of the length of the clamp, indicated at 13, is bowed or sprung in the direction of the length and the end portions have two transverse bends. 40 marking off two sections 14 and 15. When the clamp is placed around the body of the condenser, the sprung portion 13, will have its convex face directly in contact with the outer face of the cover plate 3; the sections 14 extend across the edges of the plates 2, 3 and 4 and lie in the recesses 10, 11 and 12, and the portions 15 are forced against the face of the plate 2. In some instances, the sections 14 may be longer 45 than the thickness of the body of the condenser and under such circumstances the sections 15, to make them grip the plate 2 tightly, will have to be bent against this plate sharply, as indicated in Figure 12. 50 Such a clamp can be employed to embrace condensers having bodies of different thicknesses, to enable the condenser to be made up in different capacities. Obviously, if the body of the condenser is as thick as the 55 length of the portions 14, the portions 15 will simply be turned over substantially at right angles to the portions 14, and the sharp corner or acute angle between the portions 14 and 15 shown in Figure 12, will 60 not appear. As this clamp is constructed

and designed, the plates are held together tightly not only at their opposite edges, but the middle or sprung portion of the clamp engages tightly and firmly the top of the cover plate 3 over its entire width. 70

The clips 7, as indicated particularly in Figures 1, 2, 3, 4 and 10, are substantially triangular in outline to correspond with the shape of the extension 6. Each clip has a flat main or body portion 16, one edge of 75 which is turned up at 17 and then over, as at 18, to provide an imperforate flange or portion, to press down upon the edge of the plate 3. These clips also have portions 19 along their opposite converging edges, 80 which pass down across the converging edges of the extension 6; the portions 16 having openings 9 to register with the openings 9 in the extensions 6; and from the converging edges and between the portions 85 19 extend tips 20, having perforations 21, these tips constituting fastening lugs, to enable conductors to be connected to the clips. The clips are preferably made of some electrical conducting material, and one clip will 90 be joined to the sheets of tin foil of one polarity in the condenser; while the other clip will be electrically connected to the remaining sheets of tin foil of opposite polarity. The tips 21 may also be employed 95 to mount the condenser on supports.

Figures 7, 8 and 9, considered along with Figures 5 and 6, show the manner in which the conductive and dielectric elements of the stack 1 are mounted upon the plate 2, 100 and electrically connected to the clips 7. The numeral 22 in Figure 7 indicates a sheet of tin foil of less width than the width of the plate 2, measured between the recesses 10, and this sheet is laid upon the plate 2, 105 so that one end extends out upon the extension 6. This end is turned down, so that the portion 26 thereof, between the curved broken lines 27, lies against the converging edges of the extension 6, and the corners at 110 this end of the sheet 22 are trimmed off. The opposite extremity of this sheet 22 will terminate short of the points at which the side edges of the plate 2 converge to form the opposite extension 6; that is to say, the 115 opposite end of this sheet of tin foil 22 will about coincide with a broken line joining the points 23 in Figure 5. On top of the sheet 22 is then laid a sheet of mica 24, which is wider than the sheet 22, being substantially of the same width as the plate 2, measured between the recesses 10; and this sheet of mica will be long enough to 120 extend the entire distance between the points 23 where the lateral edges of the plate 22 converge to provide the tapering extension 6; that is, when the sheet of mica 24 is laid upon the sheet of foil 22, the position of the extremities of the sheet of mica will be as 125 indicated by the broken lines 28 in Figure 130

5; and it will therefore be seen that one end of the sheet of mica overlaps the end of the sheet of foil 22, which is the inner end of the sheet of foil and does not extend out to lie in contact with the one extension 6. Similarly, on top of the sheet of mica 24, I lay another sheet of foil 25, one extremity of which will extend out upon the opposite extension 6 and have a similar portion 26 between the two broken curved lines 27 to be turned down against the edges of this extension and be trimmed off as before; and the opposite end of this sheet of foil 25 will be no nearer to the extension 6 than the transverse line between the points 23 at the left of Figure 5; so that the mica 24 will overlap this end of the sheet of foil 25. As many sheets of foil and sheets of mica may be employed as desired to build up a stack of the required height or thickness. Half the sheets of foil extending out at one end of the stack of the condenser to overlap the extension 6 thereat, and the other half of the sheets of foil extending out to overlap the other extension 6, and all of the overlapping portions of the two groups of tin foil sheets will be pierced as indicated at 29, in line with the openings 9, but no perforations in the mica sheets 24 are necessary. When the clips 7 are attached to the extremity 6, and the rivets 8 made fast, the clips bind the projecting ends of the tin foil sheets 22 and 25 against the two extensions, and the down-turned portions 19 of these clips will bend over the portions 26 of the tin foil sheets and press them tightly against the edges of the extensions. Of course, when the stack is built, the top and bottom sheets thereof will preferably be sheets of mica; that is, a sheet of mica is first laid on the plate 2 and then sheets of foil and mica in alternation, the last sheet on top of the stack directly under the spring plate also being a sheet of mica or any other suitable dielectric substance.

As shown in Figure 10, the flange or portion 18 of each clip 7 is turned over to make an acute angle with the upturned edge or portion 17; hence when the clip is fastened to the extension 6 by the rivet 8, the portion 18 will be in convergent relation to the top and face of the cover plate 2. With such a construction, these clips can be made to serve the same purpose, as the band clamp 5 for condensers having bodies of different thicknesses, so that the condenser can be made up in different capacities. If the stack is relatively thin, the flange 18 extends down and engages the cover plate 3 tightly, and if it is thicker this portion 18 simply bends up a little and fits the stack of greater thickness also. When the condenser is assembled it will ordinarily be placed in a power press to tighten the rivets 8 and to work the portions 18 of the clips and the sections 15 of

the clamp, so as to cause the plates 2 and 3 to be engaged in the required manner.

The spring plate 4 is shown detached in Figure 13 and Figure 14, which is somewhat of diagrammatic character, shows the condenser with the plate 4 curved instead of being bent flat, and with the mica and tin foil omitted, to indicate that the spring tension in the plate 4, when this plate has its convex face in contact with the condenser stack, enables uniform pressure of the desired amount to be exerted all over the area of the stack, when the securing means comprising the clips and the clamp are tightened, to press these plates and the stack together.

Figure 15 and Figure 16 show another form of spring plate, indicated by the numeral 30 and having parallel cuts made lengthwise in its opposite ends to provide a clamping portion 32, flanked by clamping portions 31 at each extremity. When this form of plate is used, the band clamp 5 is omitted. The clips 7 engage the ends of the cover plate 3 to force the cover plate down on the stack and press the plate 30 out flat; while the gripping portions 31 are turned up and bent over against the top of the cover plate 3, and the gripping portions 32 are turned over and bent against the face of the base plate 2. In this modification, the plates 2 and 3 need not be necessarily provided with the recesses 10 and 11, and I may also omit the recesses 10 and 11 and the recesses 12 as well, when the band clamp is present if desired.

Figure 17 shows another design of clip having shorter overturned portions 19 along its converging edges and having projections 33 to form spring contact devices. These projections are supported by legs 34 and have perforations 35 in their extremities. This clip is preferably made in one-piece as before, for example, by stamping out of a metal blank. When two clips of this nature are employed, the spring contacts 33 project beyond the cover plate 3 and receive in their apertures 35, the ends of a detachable resistance device, such as a grid leak 36. See Figure 18.

Figures 19 and 20 show a form of condenser in which the base plate has only one extension 6. To this extension is riveted an eyelet 8, a clip 37, which is like the clip 7, as shown for example in Figures 1 and 4, but without any portions 19 to engage the edges of the extension; and two additional clips 38 and 39 which are U-shaped receive the plates 2 and 3 with the stack 1 between them and hold the parts of the condenser together. The two clips 38 and 39 are caused to engage the opposite sides of the condenser in substantially central position and are held fast by rivets 8, which pass through the plates 2 and 3 and the stack,

to make these clips tight. This condenser may be provided with three sets or groups of tin foil sheets indicated in Figures 21, 22 and 23 at 40, 41 and 42. The sheets of 5 all three of these groups lie one over the other, between the plates 2 and 3, as indicated in Figure 20, and the sheets 40 will each have a projection or tab 43 to stick out over the extension 6 into contact with 10 the under face of the clip 37. The tin foil sheets 42 of another group, will be electrically connected to the clip 38 and the remaining tin foil sheets 41 will be connected to the clip 39. For this purpose, the sheets 15 40 will have openings 44 larger than the rivets 8 of the clips 38 and 39, so that there will be no connection between the rivets 38 and 39 and the sheets 40. Also the sheets 41 will have a large opening 44 at the right, 20 and a small opening 45 at the left, the opening 44 being large enough to give clearance to the rivet 8 of the clip 38; while the opening 45 will make contact all around the edge thereof with the rivet 8 of the clip 39. The 25 foil sheets 42 will have openings 44 at the left large enough to give clearance to the rivet 8 of the clip 39, and apertures 45 at the right, of such size as to fit the rivet 8 of the clip 38 and make contact all around 30 the edges of these apertures 45, with said rivet. By properly varying the number of sheets of foil of each group, this condenser will give different working capacities as it 35 is connected in circuit with the three groups in pairs; that is, it will have one capacity if connected through the clips 8 and 39 to make the sheets of foil 40 and 41 active, another capacity if connected through the clips 8 and 38 to make the sheets of foil 40 and 42 active. At the same 40 time, this condenser comprises a material feature in common with the other form already described, namely, a base plate preferably made of stiff insulating material and having at least one extension to which is fastened a clip serving also as a terminal 45 for conductive elements of one polarity. 50 Figure 20 indicates how the sheets 40, 41 and 42 can be used in pairs; sheet 40 and clip 37 being shown in dotted lines; sheet 41 and clip 39 in dot-and-dash lines; and sheet 42 and clip 38 in dash lines. 55 The condenser of Figures 24 to 27 inclusive, likewise has a base plate, and a cover plate with a band clamp 5 embracing the two plates to hold them together with the condenser stack between them. With this 60 type of condenser, no spring plate is used and the base plate 2 has only one extension 6. The tin foil sheets of one polarity are provided with tabs 22, which stick out over this extension and project with the extension 65 between the arms of a U-shaped clip 37.

This clip is secured by an eyelet rivet 8 passing through the tabs 22 and the extension 6. The remaining tin foil sheets of opposite polarity may have tabs which stick out from one side of the body of the condenser and can be turned over against either the base plate, or cover plate to lie under the clamp 5. This clamp has an extension 46 projecting at the opposite end of the condenser and having a hole 47 as well as a lug 75 21 to enable connections to be made to one part of the circuit; the other part of the circuit being joined to the eyelet 8, passing through the extension 6. 80

The grid leak block 48 in Figure 28, has a spring terminal thereon consisting of an upright portion 49 and a turned over base or foot 50, secured by an eyelet rivet 8 to the block 48. This contact will, of course, be of metal, and the block will have adjacent the 85 contact, an aperture 51. This block can be employed with a condenser, for example, of the kind shown in Figures 24 to 27 inclusive, by mounting the block upon the clip 37 so as to join this clip to the spring contact 90 49. For this purpose a bolt and nut can be employed, the bolt passing through the eyelet rivets in the block 48 and through the clip 38. A similar spring contact 49 can be attached to the extension 46 of the clamp 5 95 and as both of these spring contacts will have apertures 35, a grid leak can be supported by these spring contacts, the same as shown in Figure 18. Here the grid leak will be in parallel with the condenser. If the 100 grid leak block is reversed so as to secure the block upon the clip 38 by passing some suitable fastening device through the aperture 51, and the eyelet rivet in the extension 6, no direct electrical connection will exist 105 between the clip 37 and the spring contact 49, and the grid leak will then be in series with the condenser. Clip 37 is omitted in Figures 29 and 30, as the block 48 can be secured directly upon the tabs 22 in both positions by suitable means passing through the rivets 8. 110

Figures 31 and 32, show a condenser similar to the condenser of Figures 24 to 27 included, but with the member 5 having no extension 46, and with the base plate 2 provided with extensions 6 at both ends and two clips 38, to fasten down the tabs 22 and 115 25 of the sheets of tin foil of opposite polarity. 120

Figure 33 shows a condenser with only a base plate 2, having a stack thereon, a band clamp 5, and clips 7, the same as in Figures 1, 2, 3, and 4, but with no cover plate. 125

Figure 34 shows a condenser having merely a base plate with extensions at opposite ends, a stack upon this base plate encircled by a band clamp and with eyelet rivets passing through the two extensions 130

- and making contact, one with the projecting ends of the conductive sheets of the condenser of one polarity, and the other with the extended ends of the remaining conductive sheets of opposite polarity.
- Having described my invention what I believe to be new and desire to secure and protect by Letters Patent of the United States is:—
10. 1. A condenser comprising a substantially rigid insulating plate having extensions, a body of dielectric and conductive elements, and fastening means affixed to said extensions and having portions overlapping the adjacent ends of the body and set to exert pressure upon said elements to enable said elements to be held tightly against said plate.
20. 2. A condenser comprising a mounting plate having recesses in its opposite edges, elements of conductive material on said plate, and securing and clamping means encircling the condenser and entering said recesses, said securing and clamping means being shaped to enable pressure to be exerted over substantially the entire area of said elements.
30. 3. A condenser comprising a substantially rigid insulating plate having an extension, a stack of conductive and dielectric elements on said plate, and fastening means affixed to said extension and having a portion overlapping the adjacent end of the stack for causing the elements to be held tightly against said plate.
40. 4. A condenser comprising a plate and condenser elements and a clip secured to the plate, the clip having overturned portions at its edges to engage said plate, a lug projecting from one end of the clip between said edges, and an engaging portion at its opposite end to hold said elements against the plate.
50. 5. A condenser comprising a substantially rigid insulating plate having extensions, condenser elements disposed against said plate, a band clamp for the condenser engaging the plate, and clips secured to the extensions and having portions which overlap the condenser elements and exert pressure to cause said elements to be held tightly against the plate.
60. 6. A condenser comprising a substantially rigid insulating plate, condenser elements comprising sheets of conductive material, a band clamp engaging the plate to hold the condenser elements tightly against the plate, the clamp being shaped to enable pressure to be exerted over substantially the whole area of said elements, the plate having extensions, some of said sheets projecting out upon one extension, and the remaining sheets over the other, and fastening means to secure said sheets to said extensions.
70. 7. A condenser comprising a pair of insulating face plates, conductive and insulating material between the plates, said plates having recesses therein, and means for gripping the face plates along the opposite edges thereof, and having interfitting engagement with said recesses to hold the face plates in rigid position with respect to each other, said means being shaped to enable pressure to be exerted over substantially the entire area of the conductive and insulating material.
8. A condenser comprising an insulating face plate, said plate having recesses, conductive and insulating material mounted upon said plate, and means engaging the opposite edges of the plate and interfitting with said recesses to secure the plate and the conductive and insulating material firmly together, said means being shaped to enable pressure to be exerted over substantially the entire area of the conductive and insulating material.
9. A condenser comprising a substantially rigid insulating plate having an extension, condenser elements disposed against said plate, part of which project out over said extension, a band clamp for the condenser engaging the plate, the clamp being shaped to enable pressure to be exerted over substantially the entire area of said elements and fastening means carried by said extension and engaging said projecting condenser elements.
10. A condenser comprising a substantially rigid insulating plate having an extension, condenser elements disposed against said plate, a band clamp for the condenser engaging the plate, said clamp being shaped to enable pressure to be exerted over substantially the entire area of said elements, part of said condenser elements projecting out over said extension, and a clip secured to the extension to make contact with said projecting condenser elements.
11. A condenser comprising a substantially rigid insulating plate, a cover plate, condenser elements between said plates, a band clamp engaging said plates, one of said plates having an extension, part of said elements projecting over said extension, and fastening means secured to the extension and engaging said projecting condenser elements.
12. A condenser comprising a substantially rigid insulating plate, a cover plate, condenser elements between said plates, a band clamp for the condenser engaging the plates, one of said plates having extensions, part of said conductive elements projecting out over one of said extensions, and part projecting out over the other, and fastening means carried by the extensions and engaging the adjacent projecting condenser elements.
13. A condenser comprising a substantially rigid insulating plate having an exten-

1. A stack of conductive and dielectric elements on said plate, fastening means affixed to the extension and engaging some of the conductive elements and securing the ends thereof against said extension, and metallic clamping means extending transversely of the condenser and engaging the opposite side edges thereof, said clamping means being shaped to enable pressure to be exerted over substantially the entire area of said elements.
2. A condenser comprising a base plate and a cover plate of substantially rigid insulating material, condenser elements between said plates, the base plate having an extension, fastening means affixed to the extension and securing the ends of part of said condenser elements thereto, and metallic clamping means extending transversely of the condenser and engaging the opposite sides thereof, said clamping means being shaped to enable pressure to be exerted over substantially the entire area of said elements.
3. A condenser comprising electrically conductive elements separated by insulation, a resilient element, an insulating cover plate for said conductive elements and said resilient element, and clamping means substantially encircling said conductive elements and said resilient element, engaging the cover plate to hold said conductive elements and said resilient element under compression.
4. A condenser comprising electrically conductive elements separated by insulation, a curved spring plate associated with said elements, an insulating cover plate for said elements and said spring plate, and clamping means substantially encircling said elements and said plate, engaging said cover plate to hold said cover plate, said elements, and said spring plate tightly together.
5. A condenser comprising electrically conductive elements separated by insulation, a resilient element, an insulating cover plate for said resilient element and the conductive elements, and clamping means substantially encircling said conductive elements and said resilient element, extending over the opposite edges of the cover plate, to hold said cover plate and all said elements securely together.
6. A condenser comprising electrically conductive elements separated by insulation, a curved spring plate therefor, an insulating cover plate for said spring plate and said elements, and clamping means substan-
- tially encircling said elements and said plate extending over the opposite edges of the cover plate to compress said elements, said cover plate, and said spring plate.
7. A condenser comprising a substantially rigid insulating plate having an extension, condenser elements disposed against said plate part of which project out over said extension, a band clamp for the condenser encircling said elements and engaging the plate to hold the elements and plate together, and fastening means carried by said extension and engaging said projecting condenser elements, said means comprising a lug projecting beyond the extremity of said extension for connecting a conductor to said condenser.
8. A condenser comprising a substantially rigid insulating plate having extensions at its opposite ends, condenser elements disposed against said plate, a band clamp for the condenser encircling the elements and engaging the plate to secure the plate and elements together, part of said elements projecting out over one extension, and part out over the other extension, and fastening means carried by each extension and engaging said condenser elements, said means comprising a lug projecting beyond the extremity of each extension, for connecting conductors to the condenser.
9. A condenser comprising a substantially rigid insulating plate, a cover plate, condenser elements between said plates, a band clamp engaging said plates, one of said plates having an extension, part of said elements projecting over said extension, and fastening means secured to the extension and engaging said projecting condenser elements, said means comprising a lug projecting beyond the extremity of the extension for connecting a conductor to the condenser.
10. A condenser comprising a substantially rigid insulating plate, a cover plate, condenser elements between said plates, a band clamp for the condenser engaging the plates, one of said plates having extensions, part of said conductive elements projecting out over one of said extensions, and part projecting out over the other, and fastening means carried by the extensions and engaging the adjacent projecting condenser elements, said means comprising a lug adjacent each extension projecting beyond the extremity thereof for securing conductors to the condenser.
11. In testimony whereof I affix my signature.

WILLIAM DUBILIER.
